UNITED STATES PATENT OFFICE.

NORMAN ISACHSON, OF ALBION, IDAHO.

INTERNAL-COMBUSTION ENGINE.

1,423,718.

Specification of Letters Patent. Patented July 25, 1922.

Application filed June 1, 1921. Serial No. 474,087.

To all whom it may concern:

Be it known that I, NORMAN ISACHSON, a citizen of the United States, and resident of Albion, in the county of Cassia, State of Idaho, have invented certain new and useful Improvements in Internal-Combustion Engines, of which the following is a specification.

My present invention relates to improvements in thermo-water cooling systems used in internal combustion engines of the motor vehicle type and aims to provide simple, economical and efficient means for preventing overheating of the engines which may 10 be easily applied to standard constructions and which will be automatic in use and not liable to get out of order.

To this end the invention includes the combination with a motor vehicle radiator 20 and the flow and return pipes to the engine water jacket, of a steam injector for increasing the circulation of the water.

An embodiment of the invention is illustrated in the accompanying drawing in 25 which—

The figure is a fragmentary side elevation.

Many of the motor vehicles in use today have their engines cooled by the thermo-water circulating system, that is, one in 30 which the heat derived from the engine causes the water to rise and flow into the upper part of the radiator where it is subjected to the cooling action of the air drawn through the radiator by the fan, the cooled 35 water flowing to the bottom of the radiator and returning by a lower pipe connection to the engine.

When the water in the system gets heated 40 up sufficiently to boil the circulation has been found insufficient to keep the engine properly cooled, such overheating frequently occurring in mountain climbing and in work at higher atmospheric temperatures or altitudes considerably above sea level, and also 45 in pulling through long stretches of sand or mud on the low gear or on warm days when traveling with the wind.

This objection I overcome by using the 50 steam generated in the radiator as a means of increasing the rapidity of the water circulation.

In the drawings 1 designates a motor vehicle radiator of the ordinary or any 55 proved type, and 2 and 3 the flow and return pipes to the engine which is shown conventionally at 4. 5 designates the usual water

overflow pipe which has its upper end extended up into suitable proximity to the filling cap 1^a. 6 designates a steam pipe 60 which has one open end located within the radiator somewhat above the upper end of the overflow pipe so as to be above the water level.

The other end of this pipe 6 extends into 65 one of the pipe connections to the engine where it terminates in or is provided with an injector nozzle. In Fig. 1 I have shown the injector nozzle 6^a as located in the pipe 2 which leads the water from the lower part 70 of the radiator back to the engine, such being my preferred arrangement.

In operation the boiling of water generates steam in the radiator and due to the restricted water overflow pipe, such steam is 75 under moderate pressure, which causes a portion of the steam to pass through pipe 6 and nozzle 6^a and by its ejector action inside the pipe 2 to increase the flow of water.

If the water overflow pipe is found too 80 large to generate sufficient pressure it may be reduced by partially stopping up or closing either end thereof as by pinching the sides of the tube towards each other.

Having thus described my invention, what 85 I claim is:

1. The combination with a water cooled internal combustion engine and its radiator and the flow and return pipes connecting the same, of an injector located in one of said 90 pipes and having a steam pipe connection to the top of the radiator.

2. In combination with an internal combustion engine and its radiator having connecting flow and return pipes, said radiator 95 having a water overflow pipe, a steam pipe having one end connected with the interior of the radiator above the upper end of the overflow pipe, and its other end connected to inject steam into one of said connecting 100 pipes in the direction of normal flow of water therein.

3. In combination with an internal combustion engine and its radiator having connecting flow and return pipes, said radiator 105 having a water overflow pipe, a steam pipe having one end connected with the interior of the radiator above the upper end of the overflow pipe, and its other end connected to inject steam into the pipe which conveys 110 water from the radiator to the engine.

In testimony whereof, I affix my signature.

NORMAN ISACHSON.
